FIG. 5.

UNITED STATES PATENT OFFICE

2,238,703

GAME

John K. McIver and Carrie Joy, Baltimore, Md.

Application July 25, 1939, Serial No. 286,453

1 Claim. (Cl. 273—126)

This invention refers to games and more particularly to those requiring exceptional skill, and the use of discs, rollers, blocks or counters, and the like, propelled to targets or goals. It has among its objects to provide a game that will have a functional playing action different and distinct from the general type of such games now in use. Another object is to provide a special form of goal equipment that will cooperate with the playing piece used in the game to give it variable actions, employed in the game as a means for calculating results and points. A further object is to have the game constructible for portable purposes and for varying the effect of the functional action of the parts. Still another object is to have an arrangement of parts in the game that will create particular interest in the observers; require unique skill and afford features of an unexpected nature. A still further object is to have the structural parts of the game equipment arranged that they will restrict the movement of the moving or propelled pieces within a certain predetermined area after the shot or move has been made in the usual manner; and to provide for a dual manner of scoring with the playing piece.

Other objects will become apparent as the invention is more fully set forth.

The conventional games of this type usually have openings in their targets or goals for the playing pieces or blocks used, that are of round form and permit the pieces to enter, no matter how they are turned at the time. The latter are of such regular form that their motions can be closely predetermined by the player and provided for. In this case, the playing pieces are of such peculiar shape and nature that their use in the established way for the game can produce many erratic movements, to upset the wishes and expectations of the users. This makes the game more amusing and attractive to all concerned. Certain effects are provided for in the goal by making their openings of special form, and thereby have special effects on the playing pieces used, under certain conditions. The openings are plural in number to enable the plays to be varied and employed with a plural quantity of markers or playing pieces. The playing pieces are of narrow cylindrical construction and are rolled during plays towards the goal on their edges. The narrowness of the area within which the axis of the center of gravity passes through and the tendency of the rolling or rotation to keep the playing pieces upright, provide a diverging influence on its travel that causes the device to

have varied movements in accordance with the force with which they are propelled and the position they are started out with. These movements of these pieces makes it difficult to direct them to the openings in the goals accurately, and even when they reach same, to make them enter suitably to get the score sought. The device is portable and may be closed on itself into a flat compact package with great facility and speed, or opened up for reuse as the case may be. The structure is relatively simple and may be manufactured easily of standard materials.

In the drawing which illustrates examples of this invention:

Figure 1 is a view in perspective of the goal members and structure of a game embodying this invention;

Figure 2 is a view in perspective of the game combined with a table structure;

Figure 3 is a detail of the joint used between adjacent wall parts for the goal structure;

Figure 4 is a sectional elevation along the line 4—4 of Figure 2;

Figure 5 is a detail of the playing missile used in this form of the invention.

Figure 6 is a detail of the strap means to hold the walls in position.

Similar reference characters refer to similar parts throughout the drawing.

In the construction shown, the goal structure of the game consists of a background member 1 with holes 2, along the edges 3 for the use of the flexible connecting cords 4, which tie in corresponding holes 22, along the edges 33 of the side wall members 11. The cords 4 are preferably of rubber rings tied together with a link 5 to make a complete joint and at the same time keep the members tightly and resiliently together without injuring themselves when being opened, closed, or used. The flexibility of the joint overcomes many difficulties of a practical nature arising in the use of the goal structure, in a simple manner, which otherwise would require special adjustments and sundries of various natures to get the same results.

A front target plate 6 is similarly secured to the edges 7 of the side wall plates 21, through the use of the cords 8, and holes 9 and 10 respectively in the plate 6 and 21 as indicated. The wall plates 21 are placed so that their free edges 12 place themselves at the joints between the background member and side wall members, and are clamped tightly there between their edges in place. The front plate has a series of vertical openings 13, which are intended for the playing pieces, which

are arbitrarily termed missiles, 14 to pass through, if in the proper position to do so. The lower portions 15 of the openings are rectangular in form and wide enough to allow the whole playing missile 14 to pass through when upright and rolling in a vertical position. The upper portion 16 of the openings are circular in contour and large enough to allow the blocks to pass through in any position, horizontal or vertical, provided they are propelled through in proper alignment therewith. 10

When mounted on a table structure 17, having legs 18, of such size as to give the top surface 18' a slant towards the front of about one inch to the foot. The goal structure is placed at the rear end portion 19 with the chamber 20, formed by the walls and plate over a sunken or depressed portion 31 made in the surface 18 as indicated. Rails 23 are provided on the surface 18 to keep the blocks 14 from rolling off it, and also to hold the goal structure to the table. The rails 23 embrace 20 the wall member 11 and hold the plates locked with them on the table, when used on same. The background member is made higher than its connecting wall members, and front plate higher than its connecting wall plates which are preferably rounded at the upper corners. The under surface of the table has apron boards 24 which reinforce it and add to the appearance of the device. 25

The missiles 14 are circular like a disc, with their thickness sufficient to permit them to roll along a flat surface if properly played, but take on an erratic movement if not sent along carefully in the proper way. They have central holes 25 bevelled as indicated for handling and other purposes, and to give a different effect when rolling along. 30

In the operation of the game, assuming the goal structure is placed directly on the floor, the parts are preferably arranged as shown in 40 Figure 1, which does not require further explanation. The players take up a position at a line about sixteen feet from the goal and roll the missiles 14 on their edges to same. The preferable manner of holding the blocks is between the 45 thumb and first finger, as the control over their travel is made more difficult in this way. The missiles roll towards the goal if they remain upright, and the conditions are right, or fall on a side and remain there. Their subsequent positions with relation to the goal determine the amount of the score. 50

The scores are determined by the following conditions and locations. If the discs strike the goal target plates without entering through the 55 openings 13, the score is five points, and so on, as outlined in the following table:

Score

1. Hit front plate	5	60
2. Partway through opening	5	
3. Through either side slot goal	10	
4. Through center slot goal	25	
5. Triple through either slot goal	50	
6. Triple through center slot goal	100	65
7. Through all slots at random goal	150	
8. Through all slots in rotation (either way)	200	
9. Passing through circles of slots	210	
10. Game, total	500	70

Rules

- (a) Any number of persons may play,
- (b) Playing distance 16 feet,
- (c) All missiles must roll all the way to score,
- (d) Each player, in turn, rolls three missiles,
- (e) No count allowed on missiles not being played at time,
- (f) Plays reversing from goal through slot, cancel previous score,
- (g) Jumping over front plate by missiles, removes player from game.

When the table is used, the forward slant of the surface 18, affects the play to a considerable degree, as the missiles roll back if they do not make a goal. This makes the game more difficult, and causes various situations to arise that are not expected and that do not happen when the missiles are run on a horizontal surface. The game, with its rules, keeps the player at tension throughout, and excites the interest to a maximum degree.

The goal is additionally protected and made rigid by the use of U-shaped straps 26, slipping under the front plate and background walls as indicated and thereby preventing the movement of same from each other. The depressed section 31 in the table serves to drop the missiles and hold them when they have passed into the goal, so they cannot return or escape from the goal under normal playing. The cords 4 and 8 are preferably of rubber or other flexible arrangement to permit their stretching and allowing the connecting walls edge portion to open up the joints and fit in between, and thus be clamped in place.

While but one form of the invention is indicated in the drawing, and two ways of using same, it is not desired to limit this application for patent to same otherwise than limited by the prior art, as it is appreciated that other forms of construction could be used that employ the same principles and come within the scope of the appended claim.

Having thus described the invention, what is claimed is:

In combination with flat-sided discs having bevelled holes therethrough, of a target device having a frontal piece with vertical straight-sided keyhole type of slots adapted to permit the discs to pass through edgewise and topped with an enlarged circular portion, said slots leading from the bottom thereof and terminating at the proximate middle of the piece, a pair of vertical walls flexibly attached to the side edges of the said piece and disposed therefrom at an angle thereto, in rearward direction, similar walls connected to the rearward side edges of the previously mentioned vertical walls and angular pointing towards the front to provide a V-like wall attachment to the frontal piece for supporting the same vertically on a horizontal surface and a background wall vertically disposed and joining the rear portions of the said walls where they meet in V-like arrangement and forming an open box-like compartment behind the frontal piece to receive the discs passing through the slots.
